Primary Examiner — Lakiya G Rogers*Assistant Examiner* — John A Voytek(74) *Attorney, Agent, or Firm* — Quarles & Brady LLP(57) **CLAIM**

The ornamental design for a dispenser, as shown and described.

DESCRIPTION

FIG. 1 is an isometric view of a top, front, and right side of an ornamental design for a dispenser;

FIG. 2 is a front elevational view of the dispenser of FIG. 1;

FIG. 3 is a rear elevational view of the dispenser of FIG. 1;

FIG. 4 is a right side elevational view of the dispenser of FIG. 1;

FIG. 5 is a left side elevational view of the dispenser of FIG. 1;

FIG. 6 is a top plan view of the dispenser of FIG. 1; and,

FIG. 7 is a bottom plan view of the dispenser of FIG. 1.

The dash-dash-dash broken lines are included for the purpose of illustrating portions of the dispenser that form no part of the claimed design.
